UNITED STATES PATENT OFFICE.

WILLIAM HENRY SCHADE, OF SAN FRANCISCO, CALIFORNIA.

DESIGN FOR AN AUTOMOBILE-LAMP.

49,835.

Specification for Design.

Patented Oct. 31, 1916.

Application filed August 2, 1916. Serial No. 112,856. Term of patent 14 years.

To all whom it may concern:

Be it known that I, WILLIAM HENRY SCHADE, a citizen of the United States, residing at San Francisco, in the county of San Francisco and State of California, have invented a new, original, and ornamental Design for an Automobile-Lamp, illustrated in the accompanying drawing, in which—

Figure 1 is a perspective view of a head-

light designed in accordance with the invention. Fig. 2 is a side elevation of the same.

I claim:—

The ornamental design for an automobile lamp, as shown.

WILLIAM HENRY SCHADE.

Witnesses:

R. W. PRICE,
A. J. SCHMITZ.
